CATAMARAN HULL

Paul F. Swenson, Sr., and Paul F. Swenson, Jr., Cleveland, and David D. Dennis, Wickliffe, Ohio, assignors to Great Lakes Sports Mfg. Company

Filed Aug. 31, 1971, Ser. No. 176,800

Term of patent 14 years

Int. Cl. D12—16

U.S. Cl. D71—1 BB

FIG. 1 is a side elevation of a catamaran hull embodying the inventive design;

FIG. 2 is a top view of the hull shown in FIG. 1;

FIG. 3 is a front end view taken on line 3—3 of FIG. 1; and,

FIG. 4 is a back end view taken on line 4—4 of FIG. 1.

We claim:

The ornamental design for a catamaran hull, as shown and described.
